LENS COVER

Reinhold Heidecke, Braunschweig, Germany,
 assignor to Franke & Heidecke, Fabrik
 Photographischer Präzisions - Apparate,
 Braunschweig, Germany, a firm

Application May 8, 1950, Serial No. 9,808

In Germany November 8, 1949

Term of patent 14 years

(Cl. D61—1)

To all whom it may concern:

Be it known that I, Reinhold Heidecke, a citizen of Germany, and resident of Braunschweig, Germany, have invented a new, original, and ornamental Design for a Lens Cover, of which the following is a specification, reference being had to the accompanying drawings forming part hereof.

Fig. 1 is a front elevational view or face view of the lens cover, in extended or unfolded condition, showing the new design;

Fig. 2 is a rear view of the same;

Fig. 3 is an edge view of the same, still in extended or unfolded condition; and

Fig. 4 is an edge view of the same in its folded or collapsed position for convenient carrying.

The dominant features of the design comprise the two rim members hinged to each other, in combination with the two central disks held in the respective rim members, these central disks, as indicated by the shading in Figs. 1 and 2, having brightly polished reflecting surfaces of convex shape on their faces shown in Fig. 1, and being concave on their faces shown in Fig. 2. Thus

when the lens cover is placed in the intended manner over the twin lenses of a camera, the polished disks give the general visual impression of lenses, and when the cover is removed from the camera and folded up as in Fig. 4, the convex polished surfaces are faced toward each other and are thus protected from being scratched or damaged.

I claim:

The ornamental design, for a lens cover substantially as shown and described.

REINHOLD HEIDECKE.
